UNITED STATES PATENT OFFICE.

SIXTEN A. ROSEN, OF WORCESTER, MASSACHUSETTS, ASSIGNOR OF ONE-HALF TO
HERMAN L. DOW, OF WORCESTER, MASSACHUSETTS.

CLOTHES-DRIER.

1,117,248.

Specification of Letters Patent. Patented Nov. 17, 1914.

Application filed June 19, 1913. Serial No. 774,607.

To all whom it may concern:

Be it known that I, SIXTEN A. ROSEN, a citizen of the United States, residing at Worcester, in the county of Worcester and State of Massachusetts, have invented a new and useful Clothes-Drier, of which the following is a specification.

This invention relates to clothes driers of the class adapted to be detachably mounted upon a convenient supporting structure, such as a stove top, and comprises a plurality of radial arms or rods mounted upon a single supporting plate.

The object of the invention is to improve and simplify the construction of such devices and to render the same readily and easily detachable from their supporting structure.

A preferred form of my invention is shown in the drawings, in which—

Figure 1 is a perspective view of the invention as applied to the top plate of a stove; Fig. 2 is a top plan view of the device one of the radial rods being omitted to show 25 the construction underneath the same; Fig. 3 is an edge view of the device looking in the direction of the arrow 3 in Fig. 2, the rods being omitted; Fig. 4 is a sectional side elevation on the line 4—4 of Fig. 2; and Fig. 5 is a partial sectional view on the same 30 line but showing a radial rod in reversed position.

This device is of exceedingly simple construction and consists of a supporting plate 35 10 and a plurality of radial rods 11. The supporting plate is provided at one edge with an integral, downwardly-offset projecting portion 12 by which the supporting plate may be mounted upon any convenient 40 supporting structure, such as the stove top 13, by passing the projection 12 through a perforation in the stove top or other supporting surface. The plate 10 is also provided near its opposite edge with a plurality 45 of perforations 14 and in the preferred form of my invention the plate 10 is also provided with a series of radial de-

pressions 15 leading from said perforations 14 to the edge of the plate as clearly shown in Figs. 2 and 3. The rods 11 are provided 50 with downwardly offset end portions 16 adapted to be inserted through the perforations 14, and by which said rods may be retained in horizontal position. The grooves 15 act to prevent swinging movement of the 55 rods 11 about the perforations 14 as centers and hold the rods in the desired radial relation, as shown in Figs. 1 and 2. When the rods 11 are not in use, they may be removed from the perforations 14 and again 60 inserted therein in reverse position as shown in Fig. 5.

It will be seen that by the use of the supporting plate 10 I am enabled to attach a plurality of rods 11 to any desired supporting structure by providing a single perforation therein.

It is evident that many modifications of this device may be made within the scope of my invention, and I do not wish to be 70 limited to the precise form disclosed in the drawings, but

What I do claim is:—

A clothes drying device comprising a 75 stove having a flat top plate with a perforation extending vertically therethrough near the outer edge thereof, a flat supporting plate having at one edge a downwardly offset attaching member effective when inserted in said perforation to support the 80 plate in horizontal position, said plate projecting beyond the edge of the top plate and being free to turn about the center of said perforation as an axis, and a plurality of rods detachably mounted in radial spaced 85 relation on said supporting plate and extending therefrom in a horizontal plane.

In testimony whereof I have hereunto set my hand, in the presence of two subscribing witnesses.

SIXTEN A. ROSEN.
